UNITED STATES PATENT OFFICE.

ANTON B. POLYANICH, OF TRUCKEE, CALIFORNIA.

TAG OR CHECK.

1,089,956.

Specification of Letters Patent. Patented Mar. 10, 1914.

Application filed February 1, 1913. Serial No. 745,659.

To all whom it may concern:

Be it known that I, ANTON B. POLYANICH, a citizen of the United States, residing at Truckee, in the county of Nevada and State 5 of California, have invented new and useful Improvements in Tags or Checks, of which the following is a specification.

This invention relates to tags or checks, and particularly to fasteners therefor, the 10 object of the invention being to provide a shipping tag, baggage check or other tag or check provided with an improved form of fastener, whereby the tag or check may be securely applied to the article to which it is 15 to be attached, and a simple, cheap, reliable and secure fastening afforded.

The invention consists of the features of construction, combination and arrangement of parts hereinafter fully described and 20 claimed, reference being had to the accompanying drawings, in which:—

Figure 1 is a perspective view showing a tag or check provided with my improved fastener. Figs. 2 and 3 are detail sections 25 on the lines 2—2 and 3—3 of Fig. 1. Fig. 4 is a perspective view of the fastener removed.

Referring to the drawing, 1 designates a tag or check of any approved type, which is 30 shown in the present instance as provided with a reinforcing eyelet 2, and 3 designates my improved fastener.

The fastener is preferably formed of a single piece of malleable sheet metal and 35 comprises a substantially rectangular attaching portion or body 4 provided at each of its corners with securing tongues 5 and having at its center other securing tongues 6, struck up from said body 4. At one of its sides the 40 body is also provided with a pair of staples 7, and at its diametrically opposite side is formed with an attaching strip or strap 8 provided at its free end with one or more openings 9.

45 As shown, the body 4 of the fastener bears against one side of the tag or check 1,

and the tongues 5 are passed through the tag and bent or clenched against the opposite side thereof. The tongues 6 may or may not be employed, but when employed may 50 be arranged to register with the opening in the eyelet 2, through which they are passed and clenched against the face of the eyelet. The staples 7 project through the body of the tag for engagement with one of the openings 9 in the free end of the strip 8, which is adapted to be bent into loop-form for engagement with the article to which the tag is to be attached and to be held in such form by passing the staples through one of the 60 openings 9 and bending the staples laterally to hold the free end of the strip confined as will be readily understood.

It will be seen from the foregoing description that the invention provides a tag or 65 check having a fastener of novel form which is securely attached thereto, which may be easily connected with the article to which it is to be attached, and in which provision is made for holding the free end of the strip 70 8 confined so as to prevent accidental disengagement with the tag or check from the article, while permitting it to be removed when occasion requires. The advantages of the invention will be accordingly readily appreciated.

I claim:—

The combination with a tag, check or like article, of a fastener comprising a body portion, a bendable tongue integral with the 75 body portion and having an opening in the free end thereof, and staples integral with said body portion and passing through the tag or check and also through the opening in said tongue.

In testimony whereof I affix my signature in presence of two witnesses.

ANTON B. POLYANICH.
